DESIGN FOR A LIGHT REFLECTOR

Erwin Bruno Kolodzey, Detroit, Mich., assignor
to Lincoln Manufacturing Company, Detroit,
Mich., a corporation of Michigan

Application April 27, 1934, Serial No. 51,542

Term of patent 3½ years

To all whom it may concern:

Be it known that I, Erwin Bruno Kolodzey, a citizen of the State of Germany, residing at Detroit, county of Wayne, and State of Michigan, have invented a new, original, and ornamental design for a Light Reflector, of which the following is a specification, reference being had to the accompanying drawing forming part thereof.

Figure 1 is a side elevation of my light reflector, and

Figure 2 is a plan of my light reflector.

I claim:

The ornamental design for a light reflector as shown.

ERWIN BRUNO KOLODZEY.
